FISH LURE

Fred L. Churchman, 2820 Alaska St., Baton Rouge, La.
70803, and Garney B. Glasgow and Max A. Glasgow,
both of P.O. Box 353, Ville Platte, La. 70586

Filed Dec. 15, 1969, Ser. No. 20,510

Term of patent 14 years

Int. Cl. D22—07

U.S. Cl. D22—27

FIG. 1.

FIG. 2.

FIG. 3.

FIG. 1 is a front elevational view of a fish lure embodying our new design,

FIG. 2 is a side elevational view, and

FIG. 3 is a rear elevational view thereof.

The broken lines are for illustrative purposes only.

We claim:

The ornamental design for a fish lure, substantially as shown and described.
